UNITED STATES PATENT OFFICE.

RUBEN C. M. HASTINGS, OF COLUMBUS, OHIO; ELIZABETH F. HASTINGS EXECUTRIX
OF THE WILL OF SAID R. C. M. HASTINGS, DECEASED.

TELEPHONE SYSTEM.

Application filed July 3, 1920, Serial No. 393,907. Renewed April 12, 1926.

My present invention relates to improvements in telephone systems, one object of the invention being the provision by means of which the battery at the exchange is utilized 5 to operate the call-up alarm in the substation, thus relieving the system of the great objections to the call-up alarm and ringing set now employed at the exchange and producing a system which costs considerably 10 less to install, operate, and maintain than at present.

A still further object of this invention is the provision of a novel means located at the exchange for operating a step-by-step 15 device in the substation whereby the call-up alarm is connected to or dis-connected from the line and whereby the call-up alarm is continually rung without the necessity of a ringing key at the exchange after the step- 20 by-step device is operated and as long as the receiver is on the hook.

A still further object of this invention is the provision of a telephone system having located at the exchange station means controlled by the plug and switch to close and open a call alarm circuit at the substation, the alarm in the circuit being operated by the 25 battery or electrical source at the exchange.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the accompanying drawings:

40 Figure 1 is a diagrammatic view of an exchange and a substation, with the parts in normal condition, that is, previous to the substation being called or the substation calling the exchange.

45 Figure 2 is a similar view showing the parts in the position they assume during the calling of a substation.

50 Figure 3 is a similar view to Figure 1, showing the parts in the position they assume during the talking or after the called substation has removed the receiver from the hook.

55 Figure 4 is a similar view showing the position the parts assume after the receiver has been returned to the hook.

Figure 5 is a similar view showing the parts in the position they assume when a subscriber is calling.

In describing the present invention the various steps in operation will be described 60 in sequence so that the whole arrangement can be more fully understood. Figure 2 will, therefore, be first referred to in that it shows the system in the position it assumes from the normal position of Figure 1 to the 65 calling position, at which time the calling plug 100 has been operated to perform the following operation, that is, to connect the generator 1 so as to operate the step-by-step electro-magnet 17 in the substation. The circuit for operating this is closed during the insertion of the plug 100 at contact 8 of the jack and the sleeve of the plug. When the plug is inserted and the sleeve 48 engages the contact 8, the relay 9 is energized through 70 the following circuit, which includes the battery 41, the conductor 42, the contact 43, the armature 44, the resistances 45 and 46, the conductor 47, the sleeve 48, the contact 8, the relay 9, the conductor 53, the grounds 75 54 and 55, and the conductors 56 and 57. Battery is then supplied to the relay 9, the circuit thus formed including the alternating current generator 1, the conductor 3, the contact 4, the switch 5, controlled by the relay 9, the conductor 7, the conductors 13 and 14, the conductor 20, the condenser 19, which is impermeable to direct current but permeable to alternating current, the conductor 18, the electromagnet 17, the conductors 16, 90 15, 12 and 2. When the contact 5 is attracted by the relay 9 it wipes contact 4, thus momentarily closing the generator circuit.

This impulse sent out on the line during the intermittent engagement and opening 95 of the contacts 4 and 5 causes the electro-magnet 17 to be energized so that the armature 35 is operated to in turn control through the detent carrying member 36 the operating and arresting ratchets and pawls 37 and 100 37' of the step-by-step device, which in turn controls the shaft 38 and the disk 39, such disk being provided with the operating pins 39'. This action causes the pin 39' to close the contacts 28 and 29, which as shown in 105 full lines in Figure 2, connects in circuit with the line wires 14 and 15, the call-up alarm 22, the conductor 21 being connected to the conductor 15 so that current from the battery 41 will be led through the conductor 79 110

the relay 78 and the conductor 77, through the calling plug 100, conductors 12, 15 and 21, the call-up alarm 22, the conductor 23, the contacts 28 and 29, the conductor 30, the armature switch 31, the conductors 34, 14 and 13, the calling plug 100, the conductor 76, and the conductor 56 to the ground 55. It will thus be seen that as long as the calling plug is in the socket and the receiver 61 is upon the hook 64, that the call-up alarm 22 will be energized from the exchange battery 41. As soon as the receiver is removed from the hook and the hook elevates, the switch 24 will momentarily close the circuit through the contact 25 and thus the shunt to the call-up alarm 22 will be closed, as indicated in Figure 3, and inasmuch as the closing of this circuit prevents the flow of current to pass through the call-up alarm 22 the bell cannot ring while the receiver is off the hook. This circuit includes the side of the line 15, the conductor 70, the relay 33, the conductor 32, the conductor 26, the contacts 25 and 24, the conductor 27 and the conductor 72 to the ground. This circuit is closed momentarily and establishes the holding circuit which includes the conductor 70, the relay 33, the conductor 32, the armature 34, the conductor 71, and the conductor 72 to the ground. The armature 31 is attracted at the same time and the call-up alarm circuit is held open as long as the receiver is off the hook. The talking circuit includes, as clearly shown in full lines in Figure 3, the battery 41, the conductors 57 and 76, the calling plug 100, the conductors 13, 14 and 67, the induction coil 59, the conductor 66, the contact 65, the receiver hook 64, the contact 63, the conductor 62, the receiver 61, the conductor 60, the coil 59, the conductors 58, 15 and 12, the calling plug 100, the conductor 77, the coil 78, and the conductor 79.

The circuit for controlling the energization of the cut-off relay 52, includes the battery 41, the conductor 42, the contact 43, the armature 44 held closed by the electromagnet 78, the resistances 45 and 46, the conductor 47, the sleeve contact 48 of the calling plug 100, the sleeve 49 of the multiple jack 200, the conductors 50 and 51, the cut-off relay 52, the conductor 53, the grounds 54 and 55, and the conductors 56 and 57. The exchange station is provided in addition to the mechanism herein set forth, with the answering plug 101, the answering jack or socket 201, the line relay 80, the pilot relay 81, the line pilot lamp 82, the line lamp 83, the supervisory lamps 84 and 85, and the listening key 86.

When the conversation is at an end and the receiver has been returned to the hook, as shown in Figure 4, the current will flow from the battery 41 as indicated in full lines so that although the switch 24 has momen-

tarily closed the circuit through contacts 25, the armature switch 31 is still held open due to the energization of the electro-magnet 33, the withdrawal of the calling plug 100 again closing the contacts 4 and 5, by the de-energization of the relay 9 and the generator 1 for an instant is connected to the line to cause the energization of the electro-magnet 17 and the operation of the step-by-step device so that the pins 39' permit the contacts 28 and 29 to open and thus insure the opening of the shunt that controls the electro-magnet 33 and the call-up alarm 22, while at the same time the contacts 48 and 49 are open, causing the de-energization of the cut-off relay 52.

As clearly shown in Figure 5, the heavy line indicates the full current when the subscriber is calling the exchange and the receiver hook 64 is elevated, the circuit including in this instance, the battery 41, the conductor 87, the line relay 80, the conductor 88, the armature 5', the conductors 89 and 14, the telephone set at the substation, the conductors 58, 15 and 90, the armature switch 91 of the cut-off relay 52, the conductor 53, the grounds 54 and 55, and the conductors 56 and 57.

The step-by-step mechanism at the substation includes a device somewhat similar to that shown in my U. S. Patent No. 1,061,286, dated May 13, 1913, the pawl and ratchet construction being similar and being disposed so that the energization of the electromagnet 17 will move the shaft 38 counter clockwise the distance of one tooth while the spring will operate the arresting pawl in the opposite direction one tooth, the disk 39 only being propelled counter-clockwise with the pins 39' arranged so as to close the contacts 28 and 29 upon one energization of the electromagnet 17 and being released upon the next energization thereof, that is, as the jack plug is inserted and withdrawn.

From the foregoing description, it is evident that with a telephone system arranged according to the above, that the central battery or electrical source of energy 41 can be so arranged as to operate the call-up alarm 22, dispensing with the expensive ringing set at the switch board of the exchange and the necessary apparatus for operating the same or operating in conjunction with same and that as long as the receiver is upon the hook after the calling plug has been inserted in the socket, the call-up alarm 22 will be energized, the elevating of the hook causing the deenergization thereof, and permitting the subscriber to use the wires for conversation.

What I claim as new is:

1. A telephone system including an exchange station, a direct current source therein, a substation, a call-up alarm in the substa-

tion, a step-by-step device in the substation, and a switch controlled thereby in circuit with the call-up alarm, whereby upon the insertion of the plug in the jack at the exchange said switch is closed and the call-up alarm is connected direct to the current source.

2. A telephone system including an exchange station, a direct current source therein, a substation, a call-up alarm in the substation, a step-by-step device in the substation, and a switch controlled thereby in circuit with the call-up alarm, whereby upon the insertion of the plug in the jack at the exchange said switch is closed and the call-up alarm is connected direct to the current source, a receiver hook in the substation, a receiver in the substation, an electromagnetically controlled switch at the substation, the electromagnet being normally de-energized when the receiver is upon the hook, said switch thereof being normally in circuit with the call-up alarm when its electromagnet is de-energized, and means controlled by the receiver hook for energizing the electromagnet when the hook is elevated to open the call-up alarm circuit.

3. A telephone system including an exchange station, a direct current source therein, a substation, a call-up alarm in the substation, a step-by-step device in the substation, and a switch controlled thereby in circuit with the call-up alarm, whereby upon the insertion of the plug in the jack at the exchange said switch is closed and the call-up alarm is connected direct to the current source, a receiver hook in the substation, a receiver in the substation, an electromagnetically controlled switch at the substation, the electromagnet being normally de-energized when the receiver is upon the hook, said switch thereof being normally in circuit with the call-up alarm when its electromagnet is de-energized, means controlled by the

receiver hook for energizing the electromagnet when the hook is elevated to open the call-up alarm circuit, and means controlled by the receiver hook upon the elevation thereof for connecting the source with the receiver.

4. A telephone system including an exchange station having a direct and an alternating current source, a step-by-step device at the substation including an alternating current electromagnet, a receiver, a receiver hook, a call-up alarm, a switch controlled by the step-by-step device for connecting the call-up alarm with the direct current source of the exchange station, a calling plug and a jack at the exchange station, and means controlled thereby during the insertion and withdrawal of the plug for momentarily connecting the alternating current source with the electromagnet of the step-by-step device whereby the switch is opened or closed.

5. A telephone system including an exchange station having a direct and an alternating current source, a step-by-step device at the substation including an alternating current electromagnet, a receiver, a receiver hook, a call-up alarm, a switch controlled by the step-by-step device for connecting the call-up alarm with the direct current source of the exchange station, a calling plug and a jack at the substation, means controlled thereby during the insertion and withdrawal of the plug for momentarily connecting the alternating current source with the electromagnet of the step-by-step device whereby the switch is opened or closed, and means controlled by the receiver hook for opening the call-up alarm circuit and connecting the receiver to the direct current source at the exchange station.

In testimony whereof I affix my signature.

RUBEN C. M. HASTINGS.
